US00D895680S

(12) **United States Design Patent** (10) Patent No.: **US D895,680 S**
(45) Date of Patent: ** Sep. 8, 2020

(54) **DISPLAY SCREEN OR PORTION THEREOF
WITH ICON**

(71) Applicant: **Samsung Electronics Co., Ltd.**, Suwon-si (KR)

(72) Inventors: **Sunyoung Kim**, Suwon-si (KR); **Hye Ryung Kim**, Seongnam-si (KR)

(73) Assignee: **Samsung Electronics Co., Ltd.**, Suwon-si (KR)

(**) Term: **15 Years**

(21) Appl. No.: **29/686,753**

(22) Filed: **Apr. 8, 2019**

(30) **Foreign Application Priority Data**

Oct. 12, 2018 (KR) 30-2018-0047059

(57) **CLAIM**

We claim the ornamental design for a display screen or portion thereof with icon, as shown and described.

DESCRIPTION

FIG. 1 is a front view of a display screen or portion thereof with icon showing our new design; and,

FIG. 2 is an enlarged view of the icon as shown in FIG. 1. The pair of evenly spaced broken lines depict the display screen or portion thereof and form no part of the claimed design.

1 Claim, 2 Drawing Sheets
